EDWARD A. CUNNIF, OF WALTHAM, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed April 23, 1926. Serial No. 104,191.

This invention relates to warp stop mechanisms for looms and is more particularly directed to causing loom stoppage on the occurrence of a "hitch-back" or "draw" in 5 the warp threads.

It is now the ordinary practice to provide looms with warp stop mechanisms which effect loom stoppage on the occurrence of a warp fault, such, for instance, as breakage, or undue slackness of one of the warp threads; and, it has heretofore been suggested to provide means for stopping the loom upon the occurrence of a "hitch-back" or "draw" in the warp threads. The term 10 "hitch-back" or "draw" signifies a condition of the warp threads whereby they are stuck together or crossed as they pass from the warp beam towards the weaving instrumentalities. In most cases where the warp 15 for a loom has been carefully prepared, little or no difficulty occurs by reason of "draws" or "hitch-backs", but in some cases where the warps have not received proper attention during their preparation, they are 20 liable to become stuck together by reason of the size or finishing compound, and if such condition is not remedied, faults will occur 25 in the finished fabric.

In accordance with the present invention, 30 the warp stop mechanism may embody the usual series of drop wires which are normally supported by the warp threads during weaving and on occurrence of a breakage of a warp thread or too slack warp 35 thread, means are set in action for effecting loom stoppage. In connection with this general warp stop mechanism, the present invention contemplates the utilization of a series of "hitch-back" drop wires which may be of 40 the same general construction as the ordinary drop wires but which, unlike the warp drop wires, are not supported by the warp threads. In accordance with the present invention, the "hitch-back" drop wires are arranged at each end of the series of warp 45 drop wires and one or more "hitch-back" drop wires are disposed intermediate the ends of the series of warp drop wires, and all of the "hitch-back" drop wires are supported by flexible connections with a lease 50 rod which is itself under the rearward impelling force of a series of springs which,

on the occurrence of a "draw" may yield 55 forwardly to allow the connected "hitch-back" drop wire to move into position to stop the loom.

The invention and new combination of parts will best be made clear from the following description and the accompanying 60 drawings of one good form thereof.

In the drawings:

Fig. 1 is a perspective view of a loom provided with a warp stop mechanism containing the present invention; and

Fig. 2 is a fore and aft section of a loom 65 containing the present invention.

The loom frame 1 may be of any usual construction and has mounted upon the rear portion thereof the warp beam 2 which may be conveniently supported in bearings 3 carried by the loom frame. The usual crank shaft 4, the pitman 5, connecting the crank shaft to the lay 6, and the shedding mechanism 7, may all be of usual construction, and since such parts are now well understood, 70 further description thereof appears unnecessary.

The warp threads α are taken from the warp beam 2 and are passed forwardly of the loom through the shedding mechanism to 80 the take-up, as usual, and in their course forwardly the warp threads pass over the whip roll 8 carried by the side arms 9 extending from the rock shaft 10. These parts, also, may be of usual construction. 85

Mounted upon the loom frame are the side supports 11, one at each side of the loom, and on the side supports 11 the main portions of the warp stop mechanism may be supported. In the present instance of 90 the invention, the side supports 11 have a downwardly extending base portion 12 which rests upon the upper surface of an arm 13 to which it is clamped by a set screw or bolt 14. 95

The side supports 11 afford bearings 15 for the detector shaft 16 to which is secured the detector 17, as usual. The detector shaft 16 has an arm 18 extending therefrom to which is jointed an operating rod 19 which may be actuated from a cam 20 on the lower or cam shaft 21. The train of mechanism for effecting the detecting or vibrating movement of the detector is not new and,

as shown, is of the general type now well known.

Extending between the side supports 11 are the warp supporting bars 22 upon the upper surface of which the warp threads normally rest during weaving. In the illustrated form of the invention, the side supports 11 are provided with ears 23 in which are mounted the usual lease rods 24 over and under which the warp threads *a* pass, as indicated in Fig. 2.

The warp stop mechanism in the present invention comprises a series of warp drop wires 25 which are normally supported by the warp threads during weaving, and in the present instance of the invention, two sets of such warp drop wires are shown, but it is to be understood that any suitable number of rows may be employed.

20 The warp drop wires 25 have elongated slots 26 through which pass the drop wire guides 27, the construction being such that the up and down movement of the warp drop wires may be properly directed so that on the occurrence of a breakage or too slack warp thread, the associated drop wire will move downwardly into the path of the drop wire detector 17, arrest its movement and cause loom stoppage, as usual.

30 In accordance with the present invention, the warp stop mechanism has associated with it a series of "hitch-back" drop wires which are normally supported from an extra lease rod yieldingly held towards the rear of the loom, but which on the occurrence of a "draw" in the warp threads, permits the associated "hitch-back" drop wire to move into stopping relation with the detector.

40 As before indicated, warp "draws" are not usually present in well prepared warps and so it is not necessary that every loom contain a "hitch-back" drop wire device for stopping the loom on the occurrence of a "draw" but where the warp threads have been carelessly prepared or from any other cause they should stick together, a "hitch-back" device of the present invention may be readily applied to the loom of usual construction, to stop its operation on the occurrence of a 50 "draw" in the warp.

55 Mounted upon the side supports 11 and extending upwardly therefrom are the arms or uprights 28 which may be adjustably secured to the side supports 11 by bolts 29 which pass through slots 30 in the foot portion of the uprights 28. Extending between the arms or uprights 28 is a rod 31 which is disposed above the tops of the drop wires.

60 The "hitch-back" drop wires 32 may be formed substantially the same as the warp drop wires, as indicated in Fig. 2, but since the "hitch-back" drop wires are not supported directly by the warp threads, they need not be provided with warp receiving eyes. The "hitch-back" drop wires 32 are

provided with elongated slots 33 through which passes one of the drop wire guides 27, the result being that the "hitch-back" drop wire is directed and guided in its rising and falling movements.

70 It is desirable to provide a "hitch-back" drop wire at each end of the series of warp drop wires and one or more "hitch-back" drop wires intermediate the ends of the series of drop wires. In the present instance of the invention, there are three "hitch-back" drop wires 32, as indicated in Fig. 1, one of such "hitch-back" drop wires being at the opposite end of the series of warp drop wires and another "hitch-back" drop wire intermediate the ends.

75 Back of the warp stop mechanism, as indicated in Figs. 1 and 2, there is an extra lease rod 34 which is connected to the "hitch-back" drop wires by flexible connections 35 which pass over the transverse rod 31 and may be conveniently secured to the upper end portion of the associated "hitch-back" drop wire, as clearly indicated in Fig. 2.

80 The lease rod 34 is normally under the influence of springs which serve to hold it in rearward position with permissive forward yielding movement either as a whole or at one end, the construction being such that the springs may individually yield in accordance with the location of the "draw" to permit the "hitch-back" drop wire to move to its operative position relative to the detector.

85 As indicated more clearly in Fig. 1, the lease rod 34 is under the influence of springs 36 normally acting to move the lease rod rearwardly and perforce lift the "hitch-back" drop wires into their upper inoperative position, as indicated in Fig. 1. It is usually desirable to have the same number of springs 36 acting upon the lease rod 34 as there are "hitch-back" drop wires, and when a "draw" occurs, say adjacent one end of the lease rod, that end may be moved forwardly under the yielding influence of the adjacent spring, and at such time the lease rod will turn it about the opposite end spring as a fulcrum. Each of the springs 36 is connected at one end, as at 37, to the lease rod 34 and at its opposite end to the rod or rock shaft 10, as at 38.

90 Owing to the fact that the lease rod 34 is under the influence of the springs 36, the associated "hitch-back" drop wires are normally supported above the line or series of warp drop wires, and should the loom stop, owing to a "draw" in the warp threads the loom attendant at once perceives by the lowered "hitch-back" drop wire, the cause of the loom stoppage and its location.

95 The looms now in use may be readily supplied with the present invention, simply by assembling with the warp stop mechanism the upright arms 38, transverse rod 31, the 100

extra lease rod 34, springs 36 and flexibly connected "hitch-back" drop wires.

What is claimed is:

1. In a warp stop mechanism for looms, the combination of a series of warp drop wires normally supported by the warp thread during weaving, a plurality of hitch-back drop wires each having an elongated slot, a drop wire guide passing through the slots in the 10 hitch-back drop wires, an upstanding arm at each end of the series of drop wires, a support extending between said arms above the tops of the drop wires, a lease rod, a flexible connection between the lease rod and each 15 of the hitch-back drop wires passing over the said support and normally acting to maintain the upper ends of the hitch-back drop wires above the upper ends of the series of warp drop wires that a draw in the 20 warp may be indicated by the lowered hitch-back drop wire as the cause of loom stoppage.

2. In a warp stop mechanism for looms, the combination of a series of warp drop wires normally supported by the warp threads during weaving, a hitch-back drop wire at each end of the series, a hitch-back drop wire intermediate the ends of the series, a guide rod supported above the tops of the drop wires, a lease rod, a flexible connection between each hitch-back drop wire and lease rod passing over the guide rod, a spring connected at each end of the lease rod and a spring intermediate the ends of the lease rod normally acting to support the hitch-back drop wires with their upper ends above the tops of the warp drop wires but individually yielding on the occurrence of a draw in the warp to indicate by the disappearance of the hitch-back drop wire the cause of loom stoppage, a drop wire guide, and a detector adapted to be arrested in its movement to effect loom stoppage by any unsupported drop wire.

3. In a warp stop mechanism for looms, the combination of a series of warp drop wires, a plurality of hitch-back drop wires, a lease rod, springs for holding the lease rod rearwardly, side supports, an upstanding arm mounted on each support, a guide rod extending between said arms above the tops of the drop wires, flexible connections between the lease rod and each of the hitch-

back drop wires passing over the guide rod above the drop wires and normally maintaining the tops of the hitch-back drop wires above the tops of the warp drop wires that the cause of loom stoppage may be indicated on the occurrence of a draw in the warp.

4. In a warp stop mechanism for looms, the combination of side supports, a series of warp drop wires, a hitch-back drop wire at each end of the series and a hitch-back drop wire between the ends of the series, a 65 guide rod extending between the side supports above the drop wires, a lease rod, flexible connections between the lease rod and each of the hitch-back drop wires passing over the guide rod, a spring acting upon the 70 lease rod at each end and at an intermediate point to normally support the hitch-back drop wires with their tops above the tops of the series of warp drop wires and individually yielding on the occurrence of a draw 75 in the warp to lower the hitch-back drop wire and locate the draw, and a detector adapted to be arrested to effect loom stoppage by any one of the hitch-back drop wires.

5. In a warp stop mechanism for looms, the combination of side supports, a series of warp drop wires, a hitch-back drop wire at each end of the series and a hitch-back drop wire between the ends of the series, 85 a drop wire guide extending between the side supports and passing through the hitch-back drop wires, a guide rod extending between the side supports above the drop wires, a lease rod, connections between the 90 lease rod and each of the hitch-back drop wires passing upwardly from the lease rod over the guide rod, a spring acting upon the lease rod at each end and at an intermediate point to normally support the 95 hitch-back drop wires with their tops above the tops of the warp drop wires and individually yieldable on the occurrence of a draw in the warp to locate the draw, and a detector adapted to be arrested to effect loom 100 stoppage by any one of the hitch-back drop wires.

In testimony whereof, I have signed my name to this specification.

EDWARD A. CUNNIF. 55 60 65 70 75 80 85 90 95 100
